UNITED STATES PATENT OFFICE.

RUDOLF UNFUG, OF WASHINGTON, DISTRICT OF COLUMBIA.

BUILDING CONSTRUCTION.

1,411,138.

Specification of Letters Patent. Patented Mar. 28, 1922.

Application filed August 28, 1920. Serial No. 405,295.

To all whom it may concern:

Be it known that I, RUDOLF UNFUG, a citizen of the United States, residing at the city of Washington, in the District of Columbia, have invented new and useful Improvements in Building Constructions, of which the following is a specification.

This invention relates to improvements in building construction, and it comprises a wall consisting of courses, each of said courses having a joint of concrete, concrete column members arranged thereon and extending upwardly, said column members being spaced from each other, a filling of clay or earthy material arranged between each pair of column members, and a reinforcement of wire or suitable material arranged on opposite sides of the wall, and extending into said joint.

20 The wall is of sufficient strength for all purposes and by using clay or earthy material as a part of the wall the cost is materially reduced.

Walls constructed according to the present invention are moisture proof and fire proof, and serve as a heat insulation against outside temperatures.

A further advantage of the present type of wall is its relative cheapness as compared to concrete tile or brick walls. At the same time the durability compares favorably with that of any of these types of wall construction.

These and other advantages of the invention will become more apparent from a detail description of the drawings in which:—

Figure I is a fragmentary view of a wall constructed in accordance with this invention, the same being partially broken away to clearly illustrate the details of construction, and.

Figure II is a transverse sectional view taken on line 2—2 of Figure I.

45 Referring now to the drawings by characters of reference, the numeral 1 designates the foundation or sill of a building of the usual construction.

A layer of concrete 3 is arranged on the foundation and prismatic column members 4 extend upwardly from the base at suitable intervals. The spaces 5 between the column members is filled with nearly dry clay, pref-

erably mixed with coarse gravel. This filling forms a hard unyielding mass. A sheet 55 of wire fabric 2 is arranged in the concrete layer, and extends upwardly at the front and rear of the wall. The ends of the wire fabric are arranged over the top of the course and fastened to each other. The next 60 layer of concrete placed on the top of the completed course flows through the openings in the fabric and the fabric becomes embedded therein. A wall of any desired height may be built by constructing sufficient courses.

The surface of the wall may be provided with any desired finish. As shown a scratch coat 6 of waterproofed cement mortar is applied to the wall and a second coat 7, generally called a "brown coat" is then applied. Numeral 8 designates a plaster finish.

While I have shown and described in detail, one embodiment of the invention, it is to be understood that various changes may 75 be made without departing from the scope of the invention as defined by the appended claims.

What I claim as new and desire to secure by Letters Patent is:

1. A wall consisting of courses, each course comprising a joint of concrete, spaced column members integral therewith, a filling of earthy material arranged in the spaces between said column members, facing covering said concrete and earthy material and reinforcing members surrounding said courses, said reinforcing members being embedded in said joints and facing.

2. A wall consisting of courses, each course comprising a joint of concrete, spaced column members integral therewith, a filling of earthy material arranged in the spaces between said blocks, a facing covering said concrete and earthy material, and a reinforcement of wire fabric extending along the sides of the wall and over and under each course, said fabric being embedded in said concrete joints and facing.

In testimony whereof I affix my signature in the presence of two witnesses.

RUDOLF UNFUG.
